UNITED STATES PATENT OFFICE.

FRANK A. VATH, OF CHICAGO, ILLINOIS.

COOKING APPARATUS.

1,135,473.

Specification of Letters Patent. Patented Apr. 13, 1915.

Application filed August 4, 1913. Serial No. 782,770.

To all whom it may concern:

Be it known that I, FRANK A. VATH, a citizen of the United States, residing in Chicago, in the county of Cook and State of Illinois, have invented certain new and useful Improvements in Cooking Apparatus, of which the following is a specification.

This invention relates to improvements in cooking apparatus of the electric type, and one of the objects is to simplify the same, and to provide an improved, simple, durable, light and portable device of this character, which will be effective and efficient in operation, and one in which the ordinary radiator vacuum heating element or lamps may be employed as the source of heat.

A further object is to provide an improved, simple and effective device of this class in which the radiator elements may be controlled at will to regulate the amount of heat, and in which apparatus, after the articles have started to cook, the source of heat may be cut off and the apparatus will then operate as a fireless or heat retaining cooker.

To the attainment of these ends, and the accomplishment of other new and useful objects as will appear the invention consists in the features of novelty in substantially the construction, combination and arrangement of the several parts hereinafter more fully described and claimed and shown in the accompanying drawings in which,

Figure 1 is a perspective view of an improved apparatus of this character, constructed in accordance with the principles of this invention. Fig. 2 is a vertical longitudinal sectional view of the apparatus as taken on line 2--2, Fig. 3. Fig. 3 is a horizontal sectional view as taken on line 3--3, Fig. 2. Fig. 4 is a vertical sectional view as taken on line 4--4, Fig. 2. Fig. 5 is an enlarged detail view partly in section and partly broken away of the venting device. Fig. 6 is a diagrammatic view of the circuits.

Referring more particularly to the drawings and in the present exemplification of this invention, the apparatus consists of a casing having a base 10 constructed of any desired or suitable material, side and back walls 11, 12 and a top 13. The casing is also provided with a front wall designated generally by the reference numeral 14 and the side, back and front walls, as well as the top 13 are preferably constructed of sheet material. The sides and back walls are preferably of

a single piece bent into the desired shape and the front wall 14 is connected with the side walls in any desired or suitable manner, such as by means of flanges 15 and fastening devices 16, passing through a portion of the side walls and the respective flanges. The top 13 is secured to the front wall, preferably by means of a flange 17 and fastening devices 18 fastened through a portion of the top and the flange while the rear edge of the top is preferably flanged over the upper edge of the back as at 19, and secured by fastening devices 20. The frame thus formed constitutes the outer casing of the apparatus and the front wall is provided with door openings 21 closed by means of the closures 22 which are provided preferably with transparent openings to be hereinafter described. Arranged within this outer casing and spaced from the walls thereof is another casing comprising side walls 23, back wall 24 and top wall 25. This inner casing rests upon the bottom 10 of the outer casing and which bottom also forms the bottom of the inner casing. The inner casing is of a size somewhat less than the size of the outer casing to form a space therebetween, and within which space is arranged heat insulating material 26, the space being preferably only partially filled so as to leave a dead air space 27 between the insulating material and the outer casing. The inner casing thus formed is divided into two compartments by means of spaced partitions 28 which latter are secured to the top and bottom walls thereof, and also to the back wall 24 by means of flanges 29 and fastening devices 30, the back wall 24 and the top wall 25 being respectively provided with slots 31, 32, registering with the space between the partitions 28 to permit the insulating material 26 to be placed between the partitions. A substantially U-shaped member is secured by means of fastening devices 33 to the front wall 14 of the outer casing as shown more clearly in Fig. 3 and this element 32^a may also be provided with a slot 34 through which the insulating material 26 may be inserted into the space between the element and the front 14. The partitions 28 are secured to this element 32^a by means of flanges 35 and fastening devices 36. In assembling this portion of the mechanism, the elements 23, 24, 28, 32^a, and 14 may be secured together and then the insulating material 26 applied thereto,

which material is preferably in plastic form. The outer casing may then be secured in position. The structure thus formed embodies two compartments 37, 38 which are 5 insulated from each other, and one of the door openings 21 is provided for each compartment.

The source of heat in the present invention embodies vacuum heating elements or 10 radiator lamps 39 of the ordinary and well known construction, and it is one of the objects of the present invention to provide a device of this character in which these heating elements may be utilized as the source 15 of heat and to provide a means whereby any inexperienced person may readily remove one or more of the elements and replace them as the necessity requires. These heating elements 39 project through suitable openings 20 in the bottoms of the respective compartments 37, 38, and are preferably arranged close to the dividing partition between the compartments. The openings through which the elements extend, are of a size slightly 25 larger than the elements, so as to form an air space therearound for admitting outside air into the compartments, to ventilate the latter. The extremities of the elements project through the openings and engage any 30 suitable sockets 40 which latter are supported by brackets 41 which in turn are supported by a frame 42 having legs 43, and upon which frame the casing rests. The frame is 35 preferably of such a size that the lower portions of the side, back and front walls of the casing will overhang the frame, as shown more clearly in Figs. 2 and 4, and thereby hold the parts against accidental displacement, but permitting the casing to be removed 40 from the frame when desired.

The elements 39 are placed in position from the inside of the respective compartments and in order to protect the elements against injury from articles being placed in 45 the compartments, a removable partition 44 preferably of a reticulated structure is provided in each compartment. These partitions are removably held in position by means of suitable guide ways 45, so arranged that when the closures are opened, the partitions may be readily removed 50 through the openings 21 to permit access to the elements.

In order to reduce the space which is to 55 be heated adjacent the elements, the partitions 28 may be deflected as at 46, to any extent, and the elements 39 may be arranged close to each other. The source of electric energy is supplied to the elements through 60 the conductors 47, 48, connected to a suitable socket 49 into which socket a plug 50 is adapted to be inserted and which plug is electrically connected with the line wires 51, 52. The elements 39 in each compartment 65 are connected in multiple and a three point

switch 53 is provided for each of the circuits. This switch is of the ordinary and well known type and is arranged at a convenient position at the front of the apparatus to be manipulated by the operator 70 and thereby cut out or in any one or more of the elements for controlling the temperature, as is well understood.

Arranged within each compartment are supports 54 preferably carried by one of 75 the walls of the compartment and the respective partitions 44, and heat retaining elements or plates 55 are adapted to be held in position by these supports.

A vent tube 56 is provided for each of the 80 compartments and leads preferably from a point adjacent the top thereof. This tube extends from the inside of the compartment through the wall of the casing to the outside thereof, and is provided with sets 85 of holes 57, 58, 59, the latter being controlled by a cap 60 having a slot 61 therein, the cap being so arranged that by rotating it upon the end of the tube 56, either one of the sets of apertures 57, 58, 59, will be brought into 90 communication with the slot 61 for regulating the escape of vapors. This tube 56 extends through a sleeve 62 between the walls of the inner and outer casing as shown more clearly in Fig. 5 and the tube is held in 95 position by means of a nut or collar 63 on the inside of the compartment and a similar nut or collar 64 on the outside of the casing, the sleeve 62 serving as a brace or support for the walls of the casing to prevent injury 100 when the collars 63 and 64 are being adjusted.

The closures 22 are provided with transparent panels 65, any number of which may be employed, but three are shown herein. 105 These panels 65 are secured in a frame 66 which is adapted to be inserted into an opening in the closure, as seen more clearly in Fig. 3. The frame 66 is provided with a flange 67 which rests against the outer face 110 of the closure and the frame and panels may be held against accidental displacement in any suitable manner such as by means of a plate 68 arranged adjacent the inner face of the closure and abutting the inner end of 115 the frame 66 and which plate is secured to the frame and closure by means of suitable fastening devices 69.

With this improved construction it will be manifest that a very light structure is 120 provided and by the provision of the vapor outlet 56, and the elements 55, two different cooking operations may be performed simultaneously within the same compartment. This is accomplished by arranging the elements 55, shown in the right hand compartment in Fig. 2 in the manner as shown and by placing the article to be baked upon the lower element, and the article to be boiled upon the upper element. The current is 125 130

then turned on and after the required amount of heat is supplied to the compartment, and the articles begin to cook, the current may be then shut off and the cooking will then proceed in the same manner as in the ordinary fireless cooker. The vapor arising from the articles in the upper portion of the compartment will pass out of the tubular member 56 and will not come into contact with the articles in the lower portion of the compartment.

Obviously the current may be allowed to remain on during the cooking operation, if desired.

It will further be manifest that with this improved construction any inexperienced person may readily remove or insert the elements 39, the latter being protected by the partition 44, and it is also possible to utilize the ordinary and well known vacuum heating element or radiator lamp which are well known and can be readily obtained, and the apparatus repaired in this respect without necessitating the services of a skilled mechanic. Furthermore by arranging the heating elements at the side of the compartment so that they will be above the bottom thereof, they will be out of the way and in a position in which foreign particles or substances will not drop thereon, and will also permit the bottom of the compartment to be readily cleaned without removing or disturbing the elements.

While in the present exemplification of this invention, the preferred form has been herein shown and described, it is to be understood that numerous changes may be made in the details of construction and in the combination and arrangement of the several parts without departing from the spirit of this invention.

What is claimed as new is:—

1. A domestic cooking apparatus of the character described, embodying a heat insulated casing having a compartment therein opening through one of the walls of the casing, a closure for the opening, a radiator lamp within the compartment for cooking food therein, and means outside of the casing for controlling the lamp, the said lamp being adapted to be removed from and inserted into the compartment while the said closure is closed.

2. A domestic cooking apparatus embodying a heat insulated casing, having a compartment provided with an entrance opening, a closure for the entrance opening, one or more electric radiator lamps in the casing for cooking food therein, said lamps being arranged in multiple, and means for cutting in or out one or more of the lamps, there being openings through the wall of the compartment for admitting outside air into the compartment and through which openings the lamps extend, said lamps being adapted

to be removed from and inserted into the casing when the said closure is closed.

3. A domestic cooking apparatus of the character described, embodying a heat insulated compartment having an entrance opening, a closure for the opening, one or more electric vacuum heating elements arranged adjacent and extending along one side of the compartment, a shiftable apertured partition disposed adjacent the elements for protecting them and co-operating with the wall of the compartment to form a chamber for the elements having communication with the compartment, means exterior of the compartment for controlling the elements, supports within the compartment, and heat retaining elements within the compartment and supported by said supports.

4. A domestic cooking apparatus of the character described, embodying a heat insulated compartment having an entrance opening, an apertured partition dividing the compartment into two communicating chambers, one of which is somewhat smaller than the other, said entrance opening communicating only with the larger chamber, a closure for the opening and one or more electric vacuum heating elements arranged in the smaller chamber, said elements being accessible from the outside of the compartment.

5. A domestic cooking apparatus of the character described, embodying a heat insulated compartment having an entrance opening, an apertured partition dividing the compartment into two communicating chambers, one of which is somewhat smaller than the other, said entrance opening communicating only with the larger chamber, a closure for the opening, one or more electric vacuum heating elements arranged in the smaller chamber, said elements being accessible from the outside of the compartment, a vent tube leading from the larger chamber through the wall of the compartment, and means for varying the size of the opening of the tube.

6. A domestic cooking apparatus of the character described, embodying a heat insulated compartment having an entrance opening, an apertured partition dividing the compartment into two communicating chambers, one of which is somewhat smaller than the other, said entrance opening communicating only with the larger chamber, a closure for the opening, one or more electric vacuum heating elements arranged in the smaller chamber, said elements being accessible from the outside of the compartment, supports within the larger compartment, and heat retaining elements supported by said supports.

7. A domestic cooking apparatus of the character described, embodying a heat insulated compartment, an apertured partition dividing the compartment into two

communicating chambers, said compartment having an entrance opening through one wall, said opening having communication with one of the chambers, the other 5 chamber having one or more openings through one wall thereof, a support exterior of both chambers and arranged adjacent the last recited openings, electric vacuum heating elements, one for each of the last recited openings removably arranged upon the support, said elements extending through the respective openings and into the chamber, a portion of said elements being disposed exterior of the chamber.

8. A domestic cooking apparatus of the character described, embodying a heat insulated compartment, an apertured partition dividing the compartment into two communicating chambers, said compartment having an entrance opening through one wall, said opening having communication with one of the chambers, the other chamber having one or more openings through one wall thereof, a support exterior of both chambers and arranged adjacent the last recited openings, electric vacuum heating elements, one for each of the last recited openings removably arranged upon the support, said elements extending through the respective openings and into the chamber, a portion of the said elements being disposed exterior of the chamber, the said elements being of a size somewhat smaller than the openings through which they pass to form an air passage about the elements and into the chamber.

9. A domestic cooking apparatus of the character described, embodying a heat insulated compartment, an apertured partition dividing the compartment into two communicating chambers, said compartment having an entrance opening through one wall, said opening having communication

with one of the chambers, the other chamber 45 having one or more openings through one wall thereof, a support exterior of both chambers and arranged adjacent the last recited openings, electric vacuum heating elements, one for each of the last recited openings 50 removably arranged upon the support, said elements extending through the respective openings and into the chamber, a portion of said elements being disposed exterior of the chamber, the said elements extending 55 substantially the length of the wall of the chamber and being somewhat smaller than the openings through which they pass, to form an air passage into the chamber and around the element.

10. A domestic cooking apparatus of the character described, embodying a heat insulated compartment having an entrance opening, an apertured partition dividing the compartment into two communicating chambers, one of which is somewhat smaller than the other, said entrance opening communicating only with the larger chamber, a closure for the opening, said smaller chamber having a plurality of openings through its bottom, a support adjacent to and spaced from the last recited openings, a plurality of electric vacuum heating elements supported by the support and arranged in multiple, a cut out device for controlling the elements, 75 the said elements being adapted to be removed and inserted in the chamber while the closure of the said entrance opening is closed.

In testimony whereof I have signed my 80 name to this specification, in the presence of two subscribing witnesses, on this 1st day of August A. D. 1913.

FRANK A. VATH.
